BENJAMIN HANDFORTH, OF CHICAGO, ILLINOIS.

Letters Patent No. 60,887, dated January 1, 1867.

IMPROVED PROPELLER.

The Schedule referred to in these Letters Patent and making part of the same.

TO ALL WHOM IT MAY CONCERN:

Be it known that I, BENJAMIN HANDFORTH, of Chicago, in the county of Cook, and State of Illinois, have invented a new and useful improvement in Propellers; and I do hereby declare and make known that the following is a full, clear, and exact description thereof, reference being had to the accompanying drawings, and the letters and figures marked thereon, which form part of this specification.

My said invention consists in so arranging upon a reciprocating rod or shaft, placed longitudinally at the stern of a vessel, two analogous devices, that one of said devices shall operate to propel the vessel forward as the shaft is moved backward, the other device at the same time being securely closed or arranged so as to offer but a trifling resistance; or, by a simple and ready adjustment, the last-mentioned device may be so arranged as to move the vessel backward when the shaft aforesaid moves forward, the corresponding device at such times being arranged so as to present but a trifling resistance in passing through the water. My invention further consists in a novel arrangement whereby the propelling devices may be reversed, as aforesaid, by the pilot or such other person as may have charge of the matter, when desired.

To enable those skilled in the art to understand how to construct and use my invention, I will proceed to describe the same with particularity, reference being made in so doing to the aforesaid drawings, in which—

Figure 1 represents a side elevation of my invention.

Figure 2, a longitudinal vertical section thereof; and

Figure 3, a similar section, the parts being arranged for backing water.

Similar letters of reference in the several figures, in the drawings aforesaid, denote the same parts of my said invention.

A represents a hollow shaft, supported in suitable bearings, *a*, and projecting centrally from the stern of the vessel, and having a reciprocating longitudinal sliding motion given to it by any suitable arrangement of the machinery of the engine. Near the rear end of said hollow shaft, there is fixed upon it a flaring bucket, marked B, opening rearward, which is provided with a movable valve, marked D, of rubber or any other suitable material, which may be opened and closed, as hereinafter described. The said valve D is attached to the rear end of the rod C, arranged within the aforesaid hollow shaft, as shown, by means of arms, *e e*, which pass through suitable longitudinal slots in the hollow shaft marked *c*, as shown in the drawings, so that, by sliding said rod within the shaft, the valve D may be closed, as shown in fig. 2, or opened, as shown in fig. 3, according as it may be desired to advance or back water, said reversal being effected as hereinafter set forth. At a short distance in front of the aforesaid bucket B, there are hinged to the said hollow shaft, at *g*, a radial series of arms, marked *m*, which may lie down upon and parallel with the shaft, or open out like an umbrella, the opening being towards the front, opposite the direction of the opening of the bucket B. Upon these arms is arranged a suitable flexible covering, forming a bucket, E, when expanded, as shown in fig. 3. F represents a ring secured to the rod C by means of the arms *f*, in such a manner as to compress the bucket E, and keep it from opening when the valve D is closed, but which slips off and releases said bucket E when the valve D is open. Upon the front end of the sliding-rod C is a pin, marked *h*, projecting up through a slot, *d*, in the shaft A, as shown. Above the said shaft are arranged two vertical adjustable arms or jointed stops, marked L and M, which slide up and down in suitable bearings, and are so connected by a cord, *l*, arranged upon pulleys, *p p*, and a wheel, W, that they may be raised and lowered by turning the wheel alternately and simultaneously.

When it is desired to propel the vessel forward, the devices upon the shaft are arranged as shown in fig. 2, so that the backward thrust of the shaft and bucket B in the water will have the desired effect, while the water glides easily off in the direction indicated by the arrows in said fig. 2, when the bucket is drawn back by the return stroke of the shaft. When it is desired to reverse the apparatus so as to back water, the stop M is let down into the position shown in fig. 1, the stop L being raised simultaneously, so that the forward movement of the shaft will bring the pin *h* upon the slide C, against said stop M, so that while the shaft A goes on to complete its forward movement, the slide C and valve D are checked, and the valve thrown open, and the ring F moved back from the expandible bucket E, as shown in fig. 3. When the parts are in the position last mentioned, the bucket E opens as the shaft A moves forward, and thus produces the desired result, closing at

the backward stroke, the water passing through the bucket B, as indicated by the arrows in fig. 3. When the apparatus is required to be reversed again the stop M is raised and L dropped, and the apparatus is in the same manner readjusted in the position indicated in fig. 2. To provide for the liability of the stops L and M being let down after the pin h may have passed the point, and to allow the pin to pass back on the return stroke, said stops are provided with hinges, n, which form a joint opening in the proper direction, but are rigid against pressure from the opposite side. The springs S may be used to restore the lower parts of the stops to the proper position, after being opened as aforesaid. It may be observed that, if desired, both buckets B and E might be made upon the principle shown in B, or that shown in E, or the rear bucket might be expansible, and the front one with a valve, as preferred.

Having described the construction and operation of my invention, I will now proceed to specify what I claim, and desire to secure by Letters Patent—

1. I claim, in combination with the reciprocating shaft A, the buckets B and E, arranged and operating substantially as herein described and for the purposes set forth.
2. I claim, in combination with the shaft A, and buckets B E, the arrangement of the slide C, valve D, and ring F, substantially as and for the purposes described.
3. In combination with the above, I claim the arrangement of the alternating stops L M, operating substantially as and for the purposes shown and specified.

B. HANDFORTH.
